UNITED STATES PATENT OFFICE

2,469,646

MANUALLY OPERATED ROWBOAT

William E. Hogreff, Chicago, Ill.

Application September 4, 1947, Serial No. 772,169

1 Claim. (Cl. 115—24)

1

This invention relates to row-boats, and the principal object of the invention is to provide a manually operated row-boat propelled by a rotatable propeller operable through mechanism mounted centrally therein, by a man or men seated therein, the main deck thereof being mounted upon a water-tight, unsinkable float.

Another object of the invention is to provide a boat of the kind referred to and comprising a flat, hollow basal, air filled float, preferably pointed at its forward end and formed with a longitudinally extended recess opening out through its rear end for receiving and passing a propeller and rudder, skids mounted upon the under side of the float at the sides of the recess for protecting the propeller and rudder when the boat is dragged over the beach, a deck with a flat bottom firmly mounted upon the float and over the recess thereof, the said deck including raised sides and ends and the bottom plate thereof having a trap-door formed and mounted in the rear end thereof over the recess of the float, the said trap-door being hinged at its inner or forward end to the rear margin of the bottom plate of the boat, a hand operated reciprocal rowing mechanism, including hand levers, mounted centrally upon the inner hinged end of the trapdoor and a propeller shaft journaled centrally through the trap-door and extended angularly downward at its rear end through the said open recess of the float, the forward end of the shaft being operatively connected with the rowing mechanism for rotating the shaft through the reciprocation of the hand levers of the rowing mechanism, there being a rotary propeller keyed upon the rear, lower and outer end of the propeller shaft, a rudder shaft journaled perpendicularly through the forward end of the trap-door below the upper and forward end of the propeller shaft, a rudder keyed upon the lower end of the rudder shaft, within the recess of the float, a transversely extended pedal bar medially anchored to the upper end of the rudder shaft and provided with foot pedals at its opposite ends, and rower benches supported at their ends upon the sides of the deck, forwardly and rearwardly of the rowing mechanism, the rear bench over the trap-door being hinged at one end to a side of the deck, for raising the seat to permit the raising of the trap-door.

With the stated objects in view, together with such other objects and advantages as may appear from the specification, attention is directed to the accompanying drawing, as exemplifying a preferred embodiment of the invention, and wherein

Figure 1 is a top plan view of the boat assembly.

Figure 2 is a side elevation of the assembly of Figure 1, the raised positions of the rear seat and the trap-door with attached elements being in-

2

dicated in dotted lines, and a medial section of the deck being broken out to show the rowing mechanism.

Figure 3 is a bottom plan view of the boat assembly.

Figure 4 is a detail taken on the line 4—4 of Fig. 1 on an enlarged scale, showing in side elevation one of the pair of bevelled driving gears.

Figure 5 is a transverse section on the line 5—5 of Figure 4.

Figure 6 is a transverse vertical section on the line 6—6 of Figure 5.

Figure 7 is a transverse vertical section on the line 7—7 of Figure 1.

Figure 8 is a transverse vertical section on the line 8—8 of Figure 2.

In constructing a boat in accordance with this invention, I provide an elongated, flat, hollow, air and water tight, basal float 5, of any preferred material, preferably pointed at its forward end 5a, and formed at its rear end with a longitudinally extended opening or recess 5b, for receiving and passing the propeller shaft and propeller, and rudder shaft and rudder of the boat, as later described. A pair of skid-shoes 5c are bolted at 5d to the under side of the float 5, at each side of the recess 5b and in transverse parallel alignment.

Upon the basal float, I firmly mount a deck 6, which conforms generally in plan with the shape of the float, though of slightly lesser length and width, and includes the bottom plate 6a, the vertical sides 6b, the straight rear end 6c and the pointed forward end 6d. The bottom, sides and ends may be all firmly anchored together and to the float by means of angle strips 7 bolted or welded in place, and similarly the float may be reinforced in its corners by angle strips 7, all in conventional manner, and additional support may be afforded the sides of the deck by means of flat strips 8 braced outwardly around the sides and ends and anchored in place.

At the rear end of the bottom plate 6a, a medial section is cut out over the recess 5b and conformably with the shape thereof, though not extended clear out through the rear end of the plate, a ledge 6e being left across this end. An elongated, rectangular trap-door 6f, preferably of sheet iron and formed with upturned lateral flanges 6g is pivotally mounted upon the plate 6a over the recess 5b by means of pivot bolts 9 passed through the forwardly extended ends of the flanges 6g and through the longitudinally extended metal deck strips 10 which are welded or otherwise anchored to the bottom plate 6a closely alongside the flanges 6g of the trap-door. And it is to be noted that the trap-door 6f extends well forward, as does also the recess 5b, past the transverse center line of the boat, as indicated at 6h. A pair of rower benches 11, 12, are mounted 60 and supported upon the sides 6b of the boat, the

forward bench 11 being firmly bolted in place at 13, while the rear bench 12 is hinged by one end to the side of the boat, as at 14. Thus the rear bench 12 may be readily raised for permitting the raising of the trap-door 6f for the purpose as later explained. And it is to be noted that these benches are spaced substantially apart to provide a clear intermediate space at the hinged forward end of the trap-door 6f for mounting thereon the rowing mechanism now to be described.

The rowing mechanism comprises a pair of transversely spaced and aligned shaft bolsters 15, 15a, flanged outwardly along their straight lower margins to form shoes 15b, whereby they are firmly bolted in spaced relation at each side, as at 16, to the forward end of the trap-door 6f. The bolsters are formed at their rear ends with inturned bight portions 15c, directed angularly downward and rearwardly, and are formed with the complementary bearing bosses 15d recessed semi-circularly at their meeting ends to complete the propeller shaft bearing 15e (Figure 5) for passing the perpendicular shaft 17 which passes angularly downward through the bearing 18, through the trap-door which is bored through thereat for the purpose, and through a bored hanger 18a anchored at 18b centrally to the under side of the trap-door, and into and partially through the recess 5b of the float 5, between the skid shoes 5c. A bladed rotary propeller 19 is keyed upon the rear lowered end of the shaft 17 inwardly of the skid shoes 5c, which serve to protect the propeller from injury in dragging the boat over the beach. The bolsters 15, 15a are locked together by means of bolts 15f passed through ears 15g raised integrally from the bosses 15d.

A bevelled pinion gear 20 is keyed at 20a upon the inner end of the shaft 17 within the housing formed by the bolsters 15, 15a, forwardly of and supported by the bight portions 15c of the bolsters, the bevelled teeth of the pinion gear being turned inwardly.

The bolsters 15, 15a, are bored through in transverse alignment to form the shaft bearings 15h (Figure 6), and a heavy gear carrying shaft 21 is mounted through these bearings and keyed therein as at 21a against rotation. A pair of heavy, bevelled drive gears 22, 22a, are journaled in spaced relation upon the shaft 21, inwardly of the bolsters 15, 15a, and these gears are placed in mesh at each side with the pinion gear 20. A heavy drive post 23 is bored transversely through at its lower end as at 23a for passing the shaft 21 therethrough, and upon which shaft the post is thus operatively journaled between the gears 22, 22a, as at 23b (Figure 6). An extension drive post 23c is formed with a socket at its lower end and is by this socket slipped over the upper end of the main post 23, and is keyed thereto as at 23e (Figure 4). A longitudinally extended drive bar 24 is centrally and rigidly mounted on the upper end of an extension post 23c and hand bars 24a, 24b, are mounted centrally, transversely and rigidly to the ends of the bar 24. The upper post 23c is braced at each side to the bar 24. A pair of spring-urged pawls 25, 26, (Figures 5 and 6) are pivotally pinned at 25a, 26a, within recesses 23d formed in opposite sides of the post 23, these pawls being set to work in opposite directions against the teeth of the gears 22, 22a, and are urged to the teeth by the leaf springs 27 pinned at 27a to the sides of the post 23. Thus as the post 23 is reciprocated back

and forth by the rowers, or by one rower alone, the pawls alternately and operatively engage the contiguous gear teeth at either side, and continuously rotate the intermeshed pinion gear 20 in one uniform direction, and of course also the propeller shaft 17 and propeller 19, for propelling the boat forwardly. The benches 11 and 12 are of course properly spaced relative to the hand bars 24a, 24b, to enable the rower or rowers to work to the best advantage.

A foot-operated rudder mechanism referred to generally at 28 (Figure 8) is provided, the same including a rudder shaft 28a journaled vertically down through the trap-door 6f centrally in front of the rear bench 12, and through a bearing block 28b anchored to the under side of the trap-door. The rudder blade 28c is anchored by straps 28d to the lower end of the rudder shaft 28a. A cross-bar 28e is centrally and rigidly mounted at the upper end of the rudder shaft 28a within the boat, and foot pedals 28f are rigidly mounted at the ends of this cross-bar. Thus the boat may be readily steered by the feet of the rower as seated on the rear bench 12.

If desired, a trap-door 29 may be hinged as at 29a to one margin of an opening 30 formed at the rear end of the boat between the extended rear ends 8a of the strips 8, whereby an outboard motor 31, with drive-shaft 32, propeller 33, rudder 34, and steering bar 35, may be added to the craft, the motor being attached to a block 36 secured to the rear end of the deck.

From the foregoing specification, it is thought that the construction, use and operation of the craft will be fully understood, and while I have herein shown and described a preferred embodiment of the boat, and preferred structural features thereof, it is understood that the construction and features shown may be varied, within the scope of the claim.

I claim:

A boat of the kind described, comprising a basal float, there being a recess formed longitudinally through its rear end and extended substantially inward, a deck mounted upon the float and including raised sides and ends, a trap-door over the recess of the float, the same being hinged to the boat structure for opening and closing, a rower's bench hinged at one end to a side of the boat over the trap-door, a rowing mechanism mounted in the boat forwardly of the rower's bench, and upon the forward end of the trap-door, the same including a rotary propeller shaft operatively connected at its inner forward end with the rowing mechanism and extended angularly downward and rearwardly through the trap-door into the recess of the float, said shaft being journaled through bearings extended from the boat structures, and a rotary propeller keyed upon the rear lower end of the propeller shaft within the recess of the float.

WILLIAM E. HOGREFE.
